UNITED STATES PATENT OFFICE.

THOMAS H. LEWIS AND GEORGE W. TERHORST, OF PITTSBURG,
PENNSYLVANIA.

TOY REVOLVER.

SPECIFICATION forming part of Letters Patent No. 860,517, dated October 23, 1900.

Application filed March 23, 1900. Serial No. 8,840. (No model.)

To all whom it may concern:

Be it known that we, THOMAS H. LEWIS and GEORGE W. TERHORST, citizens of the United States of America, residing at Pittsburgh, in the county of Allegheny and State of Pennsylvania, have invented certain new and useful Improvements in Toy Revolvers, of which the following is a specification, reference being had therein to the accompanying drawings.

This invention relates to certain new and useful improvements in toy pistols, and is particularly adapted for use by children for amusement.

The object of the invention is to construct a magazine toy pistol which shall be extremely simple in construction, strong, durable, efficient in its operation, and comparatively inexpensive to manufacture.

Briefly described, the invention consists of a suitable piece of metallic material formed to represent the handle and barrel of a revolver, a pivoted cylinder mounted therein and adapted to carry a series of caps, means for retaining the caps upon the cylinder, and a spring-actuated firing-pin operated by the cylinder for exploding the caps.

The invention finally consists in the novel construction, combination, and arrangement of parts to be hereinafter more fully described, and specifically pointed out in the claims.

In describing the invention in detail reference is had to the accompanying drawings, forming a part of this specification, and wherein like numerals of reference indicate corresponding parts throughout the several views, in which—

Figure 1 is a perspective view of our improved toy pistol. Fig. 2 is a side view thereof with the closure-plate open, showing the arrangement of the magazine-cylinder. Fig. 3 is a longitudinal sectional view of the pistol, a portion of the barrel being broken away. Fig. 4 is a vertical sectional view taken on the line 4-4 of Fig. 1. Fig. 5 is a front view of the retaining-plate, provided with spring-clamps for holding the caps in position. Fig. 6 is a side view thereof.

Referring to the drawings by reference-numerals, 1 indicates the handle, and 2 the barrel, of a pistol, which are formed of a piece

of suitable metallic material and provided with a recess 3, in which is mounted a magazine-cylinder 4. The cylinder 4 is pivotally connected to the pistol by means of a screw 5, and it is formed with a series of outwardly-extending trip-lugs 6, having one face straight, as at 7, and the opposite face formed in a curvilinear manner, as at 8. Arranged adjacent to one side of the magazine-cylinder 60 and upon the screw 5 is a retaining-plate 9, formed with a circumferentially-arranged series of spring retaining-clamps 10, which are suitably spaced apart and adapted to engage caps 11, arranged in the magazine-cylinder 65 between the lugs 6.

The reference-numeral 12 indicates a closure-plate which is pivotally secured to the side of the pistol, as at 13, and is adapted to cover the one side of the magazine-cylinder 4 70 and is retained in position by means of a bearing-spring 14, contacting with the forward end of the plate 12, as shown in Fig. 1. The plate 12 is provided on its forward edge with a notch 12', the one wall 13' of which 75 engages with the spring 14 when the closure-plate is in the position shown in Fig. 1 of the drawings, arresting further movement of said plate in this direction and holding the same in the closed position. As the other wall of 80 the notch has a cam-surface, the plate can be readily forced backward to the position shown in Fig. 2 of the drawings, so as to give access to the cylinder.

The upper end of the recess 3 terminates in 85 an opening 15 at the top of the pistol, through which operates a firing-pin 16, secured to one end of a leaf-spring 17, while the opposite end of this spring 17 is fastened within the recess formed in the top of the handle of the pistol, 90 as at 18. The series of lugs 6, formed in the magazine-cylinder 4, form triggers for operating the firing-pin 16. This operation is as follows: By revolving the magazine-cylinder 4 the firing-pin will ride upwardly on the 95 curvilinear face of one of the lugs 6, and the action of the spring 17 will force the pin into engagement with one of the clamps 10 and explode the cap. This operation is repeated until all the caps have been exploded, when 100 the closure-plate is opened by swinging the same backward on its pivot 13, as shown in

Fig. 2, and the cylinder is reloaded by an insertion of a cap between each pair of lugs 6 and beneath the spring-clamps, as shown. The screw 5 acts as the spindle upon which 5 both the cylinder 4 and retaining-plate 9 rotate, and by reason of the clamps 10 projecting over the cylinder between the trip-lugs the cylinder and retaining-plate are rotated in unison.

- 10 It will be observed that the action of the spring 17 will always keep the firing-pin in engagement with one of the spring-clamps and that upon revolving the cylinder the pin will be forced outwardly, as above stated, by 15 one of the lugs, and when the lug passes the firing-pin the action of the spring will cause the pin to engage the clamp and explode the cap. This action is also assisted by means of a leaf-spring 19, bearing against the spring 20 17, as shown in Fig. 3 of the drawings. The two springs are secured together to the handle of the pistol.

It is thought the many advantages of our improved magazine toy pistol can be readily 25 understood from the foregoing description taken in connection with the accompanying drawings, and it will be noted that various changes may be made in the details of construction without departing from the general spirit of our invention.

Having thus fully described our invention, what we claim as new, and desire to secure by Letters Patent, is—

- 1. In a magazine toy pistol, the combination 35 with the integral handle and barrel portion forming the body which is provided with a suitable recess, of a magazine rotatably mounted within said recess and provided with a series of peripherally-arranged trip-lugs, a retaining-plate mounted within the recess for securing a series of caps upon the cylinder, said cylinder and plate being adapted to rotate in unison, a firing-pin carried by the body portion and adapted to be operated by 40 the engagement therewith of the trip-lugs carried by the rotatable magazine, and a closure-plate pivotally connected to the handle and adapted to inclose said magazine-cylinder, substantially as described.
- 45 2. In a magazine toy pistol, the combination with the body portion, of a rotatable magazine-cylinder secured thereto and pro-

vided with peripherally-arranged trip-lugs, a retaining-plate adapted to rotate in unison with the cylinder and secure the charge of explosive caps thereon, means carried by the body portion for exploding said caps, a pivoted closure-plate carried by the body portion for inclosing said cylinder, and means for securing said closure-plate in the closed position, substantially as described.

3. In a toy pistol, the combination with the body portion having a recess, of a magazine-cylinder rotatably mounted within said recess and provided with a series of peripherally-arranged trip-lugs, said cylinder being adapted to have the explosive caps arranged on its periphery, one between each pair of trip-lugs, a retaining-plate mounted within the recess to rotate in unison with the cylinder, said retaining-plate provided with a series of circumferentially-arranged clamps extending at right angles to the plate to engage and hold the caps in position on the cylinder, and spring-actuated means carried by the body portion and adapted to be operated by the trip-lugs of the magazine-cylinder for exploding the caps carried by said cylinder, substantially as described.

4. In a magazine toy pistol, the combination with the integral handle and barrel portion forming the body which is provided with a suitable recess, of a circular magazine rotatably mounted within said recess and provided with a series of peripherally-arranged trip-lugs, a circular retaining-plate mounted within the recess to rotate in unison with the magazine-cylinder, said retaining-plate having a series of circumferentially-arranged clamps extending outwardly at right angles to the plate, one between each pair of trip-lugs and adapted to secure the explosive caps upon the periphery of said cylinder, and a spring-hammer carried by the body portion and adapted to be actuated by the trip-lugs of the magazine for exploding the caps carried on said cylinder, substantially as described.

In testimony whereof we affix our signatures in the presence of two witnesses.

THOMAS H. LEWIS.

GEORGE W. TERHORST.
